Primary Examiner — Mark A Goodwin*(74) Attorney, Agent, or Firm* — Finnegan, Henderson, Farabow, Garrett & Dunner, LLP(57) **CLAIM**

The ornamental design for a retention component, as shown and described.

DESCRIPTION

FIG. 1 is a front, top, left perspective view of a retention component showing the new design;

FIG. 2 is a cross-sectional view thereof as indicated in FIG. 1;

FIG. 3 is a cross-sectional view thereof as indicated in FIG. 1;

FIG. 4 is a rear, top, right perspective view thereof;

FIG. 5 is a rear, bottom, right perspective view thereof;

FIG. 6 is a front elevation view thereof;

FIG. 7 is a rear elevation view thereof;

FIG. 8 is a right side view thereof;

FIG. 9 is a left side view thereof;

FIG. 10 is a top plan view thereof; and,

FIG. 11 is a bottom plan view thereof.

The broken lines of uneven length shown in the drawings illustrate the boundary of the claimed design and form no part thereof. The broken lines of even length shown in the drawings illustrate portions of the retention component that form no part of the claimed design.

1 Claim, 11 Drawing Sheets(56)
